(57) **CLAIM**

I claim the ornamental design for a portable computer connection terminal with keyboard, as shown and described.

DESCRIPTION

FIG. 1 is a front perspective view of a portable computer connection terminal with keyboard of the present invention;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a cross-sectional view taken along the line 9-9 in FIG. 3 with the internal parts being omitted.

The broken lines in the drawings depict portions of the portable computer connection terminal with keyboard that form no part of the claimed design.

1 Claim, 9 Drawing Sheets
